US0D1059825S

(12) United States Design Patent (10) Patent No.: US D1,059,825 S
(45) Date of Patent:  Feb. 4, 2025

(54) CARD CASE

(71) Applicant: Jianrong Zeng, Guangzhou (CN)

(72) Inventors: Jianrong Zeng, Guangzhou (CN);
Chucan Guo, Guangzhou (CN)

(73) Assignee: Jianrong Zeng, Guangzhou (CN)

() Term: 15 Years

(21) Appl. No.: 29/966,096

(22) Filed: Sep. 30, 2024

(51) LOC (15) Cl. 03-01

(52) U.S. Cl.

USPC D3/247

(58) Field of Classification Search
